UNITED STATES PATENT OFFICE.

MORRIS A. HEIMANN AND LEO M. HENSHEL, OF ST. LOUIS, MISSOURI.

DESIGN FOR A MANTLE-HOLDER.

SPECIFICATION forming part of Design No. 34,352, dated April 9, 1901.

Application filed December 3, 1900. Serial No. 38,578. Term of patent 7 years.

To all whom it may concern:

Be it known that we, MORRIS A. HEIMANN and LEO M. HENSHEL, citizens of the United States, residing at St. Louis, in the State of Missouri, have invented and produced a certain new and original Design for a Mantle-Holder, of which the following is a specification, reference being had therein to the accompanying drawings.

Our invention relates to a new and original design for a mantle-holder.

Figure 1 is a side elevation of our design. Fig. 2 is an edge view of the same, and Fig. 3 is a bottom plan view.

As shown in the drawings, the leading or material feature of our design consists of a single strand of wire 1, suitably bent, its one

end formed into a coil 2, the wire extending downwardly and upwardly, forming a loop 3. The wire is bent at right angles at its top or upper end, as indicated by the numeral 4, and terminates in a hook 5.

Having fully described our invention, what we claim as new, and desire to secure by Letters Patent, is—

The design for a mantle-holder as herein shown and described.

In testimony whereof we affix our signatures in presence of two witnesses.

MORRIS A. HEIMANN.
LEO M. HENSHEL.
